(57) **CLAIM**

The ornamental design for a docking device, as shown and described.

DESCRIPTION

FIG. 1 is a front side elevation view of our new design for a docking device.

FIG. 2 is a back side elevation view of FIG. 1.

FIG. 3 is a left side elevation view of FIG. 1.

FIG. 4 is a right side elevation view of FIG. 1.

FIG. 5 is a top side plan view of FIG. 1.

FIG. 6 is a bottom side plan view of FIG. 1.

FIG. 7 is a front side perspective view of FIG. 1.

FIG. 8 is a back perspective view of FIG. 1.

FIG. 9 is a front perspective view of FIG. 1 with a tablet being mounted in a first position.

FIG. 10 is a front perspective view of FIG. 1 with a tablet being mounted in a second position.

FIG. 11 is a front perspective view of FIG. 1 with a tablet being mounted in a third position.

FIG. 12 is a partially enlarged view of a portion of the device thereof as shown FIG. 1;

FIG. 13 is a partially enlarged view of a portion of the device thereof as shown in FIG. 3; and,

FIG. 14 is a partially enlarged view of a portion of the device thereof as shown in FIG. 7.

The features shown in broken lines in the drawing depict environmental subject matter and unclaimed boarders and form no part of the claimed design.
